TRUSS PAD

Rudolph E. Haesly, Davenport, Iowa

Application July 24, 1950, Serial No. 175,541

18 Claims. (Cl. 128—119)

1

This invention relates to a truss pad for use in the treatment of herniae, particularly those that occur in the inguinal region.

A principal object of the invention is to provide an improved truss pad provided as a covered plate having a gently sloping portion in the form of a ramp or hump designed to lie nearly flat over the inguinal ring, holding the rupture, or hernia, in, and closing the body opening. The hump or ramp is shaped so as to lie above the pubic bone, the center rectus abdominalis and Poupart's ligament. The plate is designed to furnish a nearly flat surface over the inguinal ring, with a surrounding area to rest on the body to assist carrying varying strains caused by body movements. The plate is held to the body in a manner likened to a universal hinge which permits it to move in all directions with the body, and at the same time, maintain even pressure at the hinged point; under extreme body movement, this point will move with the body; when the body again returns to its normal position, the plate follows; during these movements, an even pressure has been maintained over the rupture. The pressure applied at the rupture, or hernia, is always uniform, it being governed by the surrounding flat area of the plate which rests on the body, and the stiffness of the spring. Under extreme body movements, such as sneezing or coughing, the plate will move with the body by tipping from the top, which brings the lower point of the plate tighter to the pubic bone, thereby preventing escapement of the intestine; when again returning to normal position, the plate having first and strongest pressure at the point of fastening, will return to position in a manner likened to a closing door, thereby pushing the intestine back in, if it has passed through the inguinal opening.

A further object is to provide a truss pad that may be simply, easily and economically manufactured, preferably of sheet metal or other relatively thin, substantially rigid or stiff material. A still further object is to provide a pad having a removable cover of resilient cushioning material, such as foam rubber.

A still further object is to provide a mounting for the pad comprising a light spring secured to the rear or reverse face of the pad at the base portion thereof and permitting movement of the plate in all directions, and applies a preferred inward pressure at the point of fastening. When the wearer is sitting, the spring permits the plate to follow the changed shape of the body over the area of the pubic bone, thereby avoiding what otherwise would be discomfort. The spring is

2

structurally and functionally balanced at each side of the median line of the pad. Specifically, it is another object to mount the spring on the pad in a novel manner so that the spring is prevented from pivoting relative to the pad and relative to the brace or girdle on which the pad is mounted.

The foregoing and other important objects and desirable features inherent in and encompassed by the invention will become apparent as the disclosure of a preferred embodiment of the invention is fully made in the following detailed description and annexed sheet of drawings.

In the drawings:

15. Figure 1 is a view of the obverse or front face of the completely assembled pad, being shown at substantially actual size.

Figure 2 is a view of the pad from its reverse face.

20. Figure 3 is a cross sectional view taken on the line 3—3 of Figure 1.

Figure 4 is an obverse face view of the truss plate by itself.

25. Figure 5 is a perspective sectional view taken on the line 5—5 of Figure 4.

Figure 6 is a sectional view taken on the line 6—6 of Figure 2, being drawn to substantially double the scale of Figure 2.

30. Figure 7 is a sectional view, drawn to double scale, taken on the line 7—7 of Figure 2.

Figure 8 is a view of the mounting spring by itself.

35. Figure 9 is a cross sectional view on the line 9—9 of Figure 4.

The truss pad comprises essentially three basic elements: a circular plate or base member 10, mounting means 12 and a removable covering pad 14. Each of these components is made up of important and novel details, as will be set out below.

40. The base member or plate 10 is preferably circular and is preferably formed of light weight, substantially thin and relatively stiff material such as stainless steel or the like. Before forming, the plate is flat and after being formed it has rising from the obverse face thereof a concavo-convex crown 16 of such shape as to be substantially symmetrical at opposite sides of a median plane passed through a diameter of the circular plate, which median plane may be taken as represented by the line 5—5 in Figure 4. On the other hand, the crown is asymmetrical at opposite sides of a plane transverse and perpendicular to the median plane; the transverse plane is represented by the line 9—9 in Figure 4.

45. The general position of the pad when worn is

that shown. Therefore, the plate has upper and lower marginal edge portions 18 and 20. The crown begins adjacent the edge portion 18 and slopes gradually outwardly as a ramp 22, blending into or adjoining a rounded peak 24 below the plane 9-9 or at the side of the plane 9-9 opposite the edge portion 18, and extending thence relatively abruptly downwardly as a relatively steep wall 26, to adjoin the marginal edge portion 20 along substantially a straight line 28. The crown when viewed from the front lies within a circle 30 and is itself substantially circular except for the portion in the zone of the steep wall 26 and straight line 28 and except for opposite somewhat straight portions 31 tangent to the circle and providing for line contact with vertical muscles and fibers in the area of the hernia. The areas 20-26-28 provide in effect a transverse hinge in the pubic region, with the peak 24 always holding the hernia. In other words, the straight line 28 may be considered a chord of the circle defining the base of the crown. The circle 30 and straight portions 28 and 31 also define the junction of the crown with that substantially circular portion of the plate that forms a marginal or bordering flange 32 surrounding or encircling the crown. This marginal flange is substantially flat and all portions thereof, including the marginal portions 18 and 20 are preferably coplanar.

Stated briefly, the general position of the crown 16 is eccentric or offset relatively to the geometrical center of the marginal flange portion 32. Therefore, the radial extent of the marginal portion 18 is substantially less than the radial extent of the marginal portion 20 as measured between the base of the crown and the circular periphery of the plate. Therefore, the marginal portion 20 provides a base portion or zone of substantial area below or adjoining the relatively steep wall 26 which itself is of substantial area. In use and when covered by the cushioning material 14, the pad rests in the region of the hernia and contacts the front and top of the pubic bone region for support thereon.

The cushioning pad or cover is preferably formed as a disk 34 of rubber or equivalent material having a peripheral flange 36 which defines an interior annular groove 38. The diameter of this groove is substantially equal to the outside diameter of the member 10 and, because of the elasticity of the annular flange 36, the covering pad may be easily assembled on or removed from the plate. The obverse face of the covering pad 14 has adhered thereto by any suitable method a layer 40 of foam rubber or equivalent material having soft cushioning properties. The removability of the covering pad is important, since it enables the user to substitute new or different covers when the original one becomes worn or is drying after being removed and washed.

The reverse face of the base or marginal portion 20 is provided with a first mounting element 42 preferably formed by a recess or depression 44 pressed in the front or obverse face of the base portion. This mounting element 42 serves as means for mounting at the reverse face of the member or plate 10, spring means 46 forming the basic element of the mounting means 12. The spring is shown by itself in Figure 8 and is preferably in the form of a wire shaped as shown to provide a pair of lower mounting portions or eyes 48 and 50 and a central mounting portion or eye 52. The spring is formed with a pair of loops 54 and 56 extending respectively from the lower

5 eyes 48 and 50 toward the central eye 52, joining the eye 52 respectively in a pair of reverse bends 58 and 60 spaced apart to define a relatively narrow throat 62. The loop portions 54-58 and 56-60 are structurally balanced at opposite sides of a straight line drawn through the eye 52 and centrally between the eyes 48 and 50.

10 The mounting element 42 is provided with a pair of spaced apertures 64 and integral portions of the material of the mounting element are formed into short sleeves 66 (Figure 7) over which the eyes 48 and 50 of the spring 46 are respectively centered. A pair of screws 68 are passed through a double apertured washer 70, through the apertured sleeves 66 and into a retaining member 72 which has a pair of spaced threaded bores therein. The means just described thus securely anchors the lower portion 15 of the spring 46 on the mounting element 42 of the reverse side of the base portion 20 of the plate 10.

20 As will be best seen in Figures 2 and 3, all portions of the spring 46 are coplanar and the extent of the spring is substantially coextensive with the cavity or recess formed by the concave shape of the reverse face of the crown 16. The eye 52 of the spring is substantially centered with respect to the center of the concavity of the crown. This eye serves as means for the mounting 25 of a second mounting element here in the form of an elongated member 74 provided with a central tapped bore which receives a screw 76 passed through the eye 52 of the spring. For the purpose of mounting the assembly on a brace or 30 girdle, the member 74 has a pair of tapped bores for respectively receiving a pair of screws 78 and 80, one above and one below the screw 76. A complementary member 82 may cooperate with the member 74 for the type of mounting referred to. The upper screw 78 passes through the throat 62 between the reverse bends 58 and 60 of the spring 46 (Figures 3 and 6), thus restraining relative pivoting between the spring 46 and the member 74 about the center screw 76.

35 As is best apparent in Figure 3, the disposition of the spring 46 is such that it lies closely parallel to the plane of the reverse face of the plate 10, resulting in a reduction in the over-all thickness of the assembly. Because of the configuration of the spring, the mounting is resiliently balanced and is arranged for appropriate flexure relative to the mounting elements 74 and 42. For example, the pad assembly is capable of flexure equally in either direction about an axis coincident with a straight line drawn through the eye 52 and centrally between the eyes 48 and 50. Because of the length of the loops 54 and 56 and the reverse bends 58 and 60, desirable resiliency is permitted about an axis transverse to the axis just referred to.

40 Since the assembly comprises relatively few parts of simple yet effective design, the cost of production will be relatively low. Each component itself is of simple design and are cooperatively associated to produce the greatest aid and comfort to the user.

45 Other features and advantages of the invention not specifically enumerated herein will undoubtedly occur to those versed in the art, as likewise will numerous modifications and alterations in the preferred embodiment of the invention disclosed, all of which may be achieved without departing from the spirit and scope of the invention as defined in the appended claims.

What is claimed is:

1. An article of the class described, comprising: a circular plate of relatively stiff material presenting obverse and reverse faces and having a concavo-convex crown rising from its obverse face so that the crown is bordered by a substantially radial flange; the junction of said flange and the base of the crown lying substantially uniformly on a circle except for a portion that lies substantially on a chord of such circle; the position of the crown on the plate being such that the radial extent of the flange is substantially uniform except at said chord portion whereat it is appreciably greater to provide a substantial base area; the shape of the crown being such that it rises abruptly as a relatively steep wall from said base area to a rounded peak and slopes thence back as a gradual ramp toward the circular portion of the junction of the flange with the base of the crown; means on the reverse face of the base area providing a mounting element; a spring lying generally in a plane parallel to the reverse face of the radial flange and anchored to said mounting element and extending to a zone substantially coincident with the center of the concavity of the crown at said reverse face; and a second mounting element secured to the spring in said zone and spaced from the plate so as to be normally out of contact with the plate.

2. The invention defined in claim 1, further characterized in that: the spring has a loop lying in the plane of the spring and said loop is so shaped and positioned as to lie substantially within the reverse side of the circular portion of the crown-flange junction.

3. The invention defined in claim 1, further characterized in that: the spring is of the wire type having opposite ends anchored to the first mounting element in close proximity to each other and has the portion thereof intermediate its ends formed as a pair of loops looped outwardly in opposite directions to either side of a straight line drawn through both mounting elements, said loops meeting in said zone in an eye for carrying the second mounting portion.

4. An article of the class described, comprising: a plate of relatively stiff material presenting obverse and reverse sides and having a concavo-convex crown rising from its obverse face, a portion of the plate bordering the crown providing a flange normal to the altitude of the crown and having obverse and reverse surfaces; means on the reverse surface of said flange providing a first mounting element; a second mounting element at the reverse face of the plate and located substantially centrally of and out of contact with the concavity of the crown and spaced from the first mounting element generally in a plane parallel to the reverse face of the plate; and spring means anchored to the first mounting element and extending toward and connected to the second mounting element for resiliently sustaining said second mounting element, said spring means in extent being within the marginal edges of the plate.

5. The invention defined in claim 4, further characterized in that: the spring means includes a loop substantially coplanar with the mounting elements, and said loop is substantially within the margin of the base of the crown.

6. The invention defined in claim 4, further characterized in that: the first mounting element has a pair of fasteners spaced apart in the plane of the elements at opposite sides of a straight line drawn between said elements; and the spring

means has a pair of coplanar loops, one at each side of said straight line, each loop having a free end secured to one of said fasteners, and said loops being joined by an intermediate portion connected to and for sustaining said second element.

7. The invention defined in claim 6, further characterized in that: said intermediate spring means portion between the loops is in the form of an eye; a single fastener passes through said eye to effect the connection of the spring means to the second mounting element; and said second mounting element has means thereon engageable with the spring means adjacent to but spaced from the eye to prevent pivoting of said mounting element relative to the spring about said single fastener.

8. An article of the class described, comprising: a circular plate of relatively stiff material having a concavo-convex crown rising therefrom within the periphery thereof so that said crown is bordered by a substantially flat radial flange; the junction of said flange and the base of the crown lying substantially uniformly on a circle except for a portion that lies substantially on a chord of such circle; the position of the crown on the plate being such that the radial extent of the flange is substantially uniform except at said chord portion whereat it is appreciably greater to provide a substantial base area; and the shape of the crown being such that it rises abruptly as a relatively steep wall from said base area to a rounded peak and slopes thence back as a gradual ramp toward the circular portion of the junction of the flange with the base of the crown.

9. An article of the class described, comprising: a circular plate of relatively stiff material having a concavo-convex crown rising therefrom inside the periphery thereof so that said crown is surrounded by a marginal flange lying substantially in a radial plane; said crown being symmetrical at opposite sides of a median plane through a diameter of the plate and perpendicular to said radial plane, but asymmetrical at opposite sides of a third plane perpendicular to both the radial and median planes and drawn through a second diameter of the plate, the shape of the crown as viewed in section along said median plane being such that the crown adjoins and slopes outwardly as a gradual ramp away from the marginal flange at one side of said third plane to a rounded peak at the other side of said third plane and extends thence relatively abruptly inwardly as a relatively steep wall to adjoin the marginal flange at said other side of said third plane.

10. An article of the class described, comprising: a circular member having a crown rising from one face thereof within the periphery thereof so that the crown is bordered by a substantially flat radial flange; the junction of said flange and the base of the crown lying substantially uniformly on a circle except for a portion that lies substantially on a chord of such circle; the position of the crown on the member being such that the radial extent of the flange is substantially uniform except at said chord portion whereat it is appreciably greater to provide a substantial base area; and the shape of the crown being such that it rises abruptly as a relatively steep wall from said base area to a rounded peak and slopes thence back as a gradual ramp toward the circular portion of the junction of the flange with the base of the crown.

11. An article of the class described, comprising: a circular member having a crown rising

therefrom inside the periphery thereof so that said crown is surrounded by a marginal flange lying substantially in a radial plane; said crown being symmetrical at opposite sides of a median plane through a diameter of the plate and perpendicular to said radial plane, but asymmetrical at opposite sides of a third plane perpendicular to both the radial and median planes and drawn through a second diameter of the plate, the shape of the crown as viewed in section along said median plane being such that the crown adjoins and slopes outwardly as a gradual ramp away from a first portion of the marginal flange at one side of said third plane to a rounded peak at the other side of said third plane and extends thence relatively abruptly inwardly as a relatively steep wall having its bottom adjoining a diametrically opposed second portion of the marginal flange at said other side of said third plane; said diametrically opposed portion of the marginal flange being of greater length than said first portion of the marginal flange to provide a substantial base area at said bottom of the relatively steep wall.

12. An article of the class described, comprising: a main body having first and second opposite marginal edge portions lying substantially in the same plane and further having a crown rising above said plane intermediate said marginal edge portions, the shape of the crown being such that it slopes upwardly as a gradual ramp from the first marginal edge portion in the direction toward the second marginal edge portion, terminating short of said second marginal edge portion in a rounded peak, and extending downwardly relatively abruptly from said rounded peak toward and adjoining said second marginal edge portion as a relatively steep wall, and said second marginal edge portion extending in said plane away from the junction thereof with said relatively steep wall a greater distance than the extent of said first marginal edge portion from its junction with the ramp of the crown so as to present a substantially greater planar area adjoining said relatively steep wall.

13. The invention defined in claim 12, further characterized in that: the crown is sloped substantially symmetrically in opposite directions transverse to the slope of the ramp and downwardly toward the plane of the marginal edge portions; and said body has third and fourth marginal edge portions coplanar with the first and second marginal edge portions and respectively adjoining the symmetrical slopes of the crown.

14. A truss pad, comprising: a body member of relatively stiff material having obverse and reverse faces and defined by marginal edges; means providing a mounting element on the reverse face adjacent one marginal edge portion; a second mounting element at the reverse face spaced from and substantially coplanar with the first mounting element and located out of contact with the body member and substantially centrally as respects all said marginal edges; and spring means extending between and having spaced portions thereof fixed respectively to the mounting elements; said spring means comprising an elongated element curled into a plurality of loops formed respectively about a plurality of axes perpendicular to the plane of the mounting elements, said loops being substantially balanced at either side of a straight line drawn through the mounting elements.

15. A truss pad, comprising: a body member of relatively stiff material having obverse and reverse faces and defined by marginal edges; means

providing a mounting element on the reverse face adjacent one marginal edge portion; a second mounting element at the reverse face spaced from and substantially coplanar with the first mounting element and located out of contact with the body member and substantially centrally as respects all said marginal edges; and spring means extending between and having spaced portions thereof fixed respectively to the mounting elements.

16. A truss pad, comprising: a body member of relatively stiff material having obverse and reverse faces and defined by marginal edges; means providing a mounting element on the reverse face adjacent one marginal edge portion; a second mounting element at the reverse face spaced from and substantially coplanar with the first mounting element and located out of contact with the body member and substantially centrally as respects all said marginal edges; and spring means comprising an elongated element curled into a loop formed about an axis perpendicular to the plane of the mounting elements.

17. A truss pad, comprising: a body of relatively stiff material throughout and having an annular peripheral flange, said flange being substantially flat and extending inwardly toward the center of the body; said body further having a crown rising from the flange inwardly of the flange periphery and including annular contiguous wall portions rising from the flange at different angles to the flange and meeting and blending into a rounded peak offset transversely of the flange so as to lie asymmetrically relative to the flange periphery; and a cover of resilient elastic material of normally uniform elasticity having an annular edge secured to the flange periphery and stretched over the peak of the crown so that the interior surface of said cover contacts the body at only said peak and said flange periphery and lies out of contact with the body intermediate said peak and flange periphery; said asymmetrical offset of the peak relative to the flange periphery and said different angles of the wall portions relative to the flange providing interior spaces of different shapes between the body and the interior surface of the cover.

18. The invention defined in claim 17, further characterized in that: one of said wall portions of the crown is at a relatively steep angle to the adjoining flange portion, and said adjoining flange portion is of greater area than other flange portions adjoining other wall portions so as to provide thereat a greater space for inward yielding of the immediately overlying cover portion.
